UNITED STATES PATENT OFFICE.

WILLIAM OUTTERSON WOOD, OF SOUTH HETTON, NEAR SUNDERLAND, ENGLAND, AND HANS KNUDSEN, OF BOSTON, MASSACHUSETTS.

METHOD OF OBTAINING DISRUPTIVE OR EXPLOSIVE EFFECTS.

No. 845,604.

Specification of Letters Patent.

Patented Feb. 26, 1907.

Application filed November 13, 1903. Serial No. 181,089.

To all whom it may concern:

Be it known that we, WILLIAM OUTTERSON Wood, a subject of the King of Great Britain, residing at South Hetton, by Sunderland, in 5 the county of Durham, England, mining engineer, and HANS KNUDSEN, a citizen of the United States of America, of Revere House, Boston, Massachusetts, United States of America, at present residing at 29^a Gillingham street, in the county of London, England, engineer, have invented an Improved Method of Obtaining Disruptive or Explosive Effects, of which the following is a specification.

15 This invention has reference to an improved method of obtaining disruptive or explosive effects for blasting purposes.

Heretofore it has been usual in blasting operations to employ cartridges composed of 20 appropriate chemical substances which when fired by a fuse or detonator will suddenly combine or react on each other so as to explode, thereby generating a large volume of high-pressure gases, the force of which performs the disruptive effect required for dislodging or rending the surrounding material into which said cartridge had previously been 25 inserted or embedded. The flame resulting from the firing of these cartridges is extremely objectionable and dangerous when they are used in dusty or fiery coal-mines, and the fumes remaining after the explosion are sometimes highly deleterious when the cartridges are used in confined places. We are 30 of course aware that it has been proposed to make the cartridges both flameless and fumeless; but these effects would be in most cases obtained at the expense of the explosive force of the cartridges—that is to say, the 35 substance required to be used with the components of the explosive compound or composition operate more or less to reduce the resulting force of explosion. Even if the said cartridges should be both fumeless and flameless there is always a high factor of danger 40 present in their use which necessitates their being carefully handled by the persons whose duty it is to employ them.

Now it is the object of our invention to dispense altogether with substances that depend upon a flame for causing their chemical combination or reaction in order to explode, so that according to our invention a detonator or fuse becomes unnecessary, no flame oc-

curs on the explosion, and the presence of deleterious fumes resulting from the explosion can be avoided. Furthermore, the danger which attends the handling of the usual cartridges is absent in our case.

For the purpose of our invention we employ liquid or other normally gaseous fluid in a liquid condition (hereinafter referred to as "liquid air" or "liquid gas") contained in or supplied to a suitable case or container of metal or other appropriate material, which is placed within a hole formed for its reception in the material to be rended, said case or container being suitably "tamped" in the well-known or other appropriate manner. The interchange of temperature that takes place between the liquid air or liquid gas (which may be at a temperature of about 312° below zero Fahrenheit) and the surrounding material to be rended causes the said liquid air or liquid gas to quickly assume its aeriform or gaseous condition and generate a heavy pressure which will burst the case or container and effect the blasting or disruptive operation.

In order that our method may be clearly understood and readily carried into effect, we will describe the same more fully with reference to the accompanying drawing, in which is shown, by way of example, in longitudinal section a case or container to receive the gaseous fluid.

In the drawing, A denotes the liquid-air case or container, which may be made of copper or steel, although we find it preferable to cast it in suitable molds, the condition of the molecules of the metal when cast being more satisfactory for insuring an effectual disintegration of the case or container when its internal pressure reaches the bursting-point than would be the case if said case or container were made by a drawing or similar operation. Moreover, by reason of the extremely low temperature to which the case or container is subjected by the liquid air or liquid gas and the consequent contraction of the metal comprising them the case or container possesses increased strength to resist internal stresses, which when overcome by the final bursting pressure will cause the case or container to be suddenly and effectually disintegrated and give rise to an explosion of great violence. The said case or container is advantageously made of cylindrical

shape, with one end closed and the other end formed with a neck a for the reception of a plug-valve a' for connecting the vent pipe or conduit a^2 to the case or container and for closing the said neck. In order to enable a tight joint to be made with the case or container by said plug-valve, the latter comprises a stem which has screw-threads a^3 at one end to engage with corresponding screw-threads at the inner end of the neck a and has at the opposite end a head a^4 , which may be made of square, hexagonal, or other suitable shape for enabling it to be readily screwed in place. The diameter of said stem between the screw-threads and the head is less than that of the internal diameter of the neck a , and it has a central bore for the reception of the vent-pipe a^2 . The inner surface of the said head a^4 has an annular surface a^5 of conical or wedge shape, which when the stem is screwed in place bears against the outer end of the neck a , and owing to the intense coldness to which said stem is subjected when in place and its consequent contraction the conical or wedge shaped annular surface a^5 very firmly seats or embeds itself against or into the said neck and forms a tight joint past which the liquid air or its vapor as it evaporates cannot escape, even under the heavy pressure that is generated within the case or container. The aforesaid vent-pipe a^2 is bent upward at its inner end, as shown in the drawings, so as to lie above the liquid air within the case or container, thus providing a passage for the liquid-air vapor, but not for the liquid air itself. This vent-pipe a^2 is made long enough to extend to a position of safety for the person using the case or container, and at its outer end it terminates in a valve-casing a^6 , which is furnished with a valve a^7 , that is adapted to open or close the passage through the said vent-pipe by the actuation of a handle or hand - wheel a^8 . While the said case or container A is being fitted with the plug-valve a' and while it is

being placed in position and tamped the said valve a^7 is left open, so that the liquid air as it evaporates can pass through the vent-pipe a^2 and escape through the openings a^9 in the valve-casing without fear of the pressure 50 within the case or container unduly rising and prematurely bursting the latter. When, however, the said case or container has been properly placed and tamped, the valve a^7 is closed. The pressure generated in the case 55 or container is thereby permitted to accumulate until it reaches the bursting-point, whereupon the said case is shattered and the rending effect obtained. The aforesaid plug-valve can in some cases be recovered and used 60 again.

What we claim, and desire to secure by Letters Patent of the United States, is—

1. A method of obtaining disruptive or explosive effects consisting in supplying 65 liquid air or liquid gas to a burstable chamber, hermetically sealing the said chamber and vaporizing its contents solely by the heat abstracted from the surrounding substance in which the chamber is placed, substantially as described.

2. A method of obtaining disruptive or explosive effects consisting in charging a cooled burstable chamber with liquid air or liquid gas, then introducing it into the substance to 75 be rended, then hermetically sealing said chamber and permitting it to abstract heat from the surrounding substance for vaporizing the contents of the chamber until the bursting pressure is reached, substantially as 80 described.

In testimony whereof we have hereunto set our hands, in presence of two subscribing witnesses, this 30th day of October, 1903.

WILLIAM OUTTERSON WOOD.
HANS KNUDSEN.
